CLAIM

The ornamental design for a ventilation conduit for toilet seats or the like, as shown and described.

DESCRIPTION

FIG. 1 is a perspective view taken from the top, front and left side of a ventilation conduit for toilet seats or the like showing my new design;

FIG. 2 is another perspective view taken from the top, front and left side thereof;

FIG. 3 is a perspective view taken from the bottom, front and right side thereof; and

FIG. 4 is a rear elevational view thereof.

The fragmentary broken line representation of a water closet and a ventilator for a water closet in FIG. 1 is for purposes of illustration only.

FIG. 1

FIG. 2

FIG. 3

FIG. 4
